United States Patent Office

Des. 222,106
Patented Sept. 28, 1971

222,106

CUTTING TOOL

Donald E. Knox, Mission, Kans., assignor to Beaver
Drill & Tool Co., Kansas City, Mo.

Filed May 4, 1970, Ser. No. 22,798

Term of patent 14 years

Int. Cl. D8—03

U.S. Cl. D54—4

Fig. 1.

Fig. 2.

Fig. 3.

Fig. 4.

Fig. 5.

FIG. 1 is a front elevational view of the cutting tool embodying my new design;

FIG. 2 is a bottom plan view thereof;

FIG. 3 is a side elevational view thereof;

FIG. 4 is a cross-sectional view thereof taken along line 4—4 of FIG. 3; and

FIG. 5 is a top plan view thereof.

I claim:

The ornamental design for a cutting tool, as shown.
